UNITED STATES PATENT OFFICE.

WILLIAM P. DUN LANY, OF CHICAGO, ILLINOIS, ASSIGNOR TO SEARS, ROEBUCK AND COMPANY, OF CHICAGO, ILLINOIS, A CORPORATION OF NEW YORK.

APPARATUS FOR PRODUCING ORNAMENTAL ROOFING.

1,214,659.

Specification of Letters Patent.

Patented Feb. 6, 1917.

Application filed November 6, 1915. Serial No. 59,933.

To all whom it may concern:

Be it known that I, WILLIAM P. DUN LANY, a citizen of the United States, residing at Chicago, in the county of Cook and 5 State of Illinois, have invented a certain new and useful Apparatus for Producing Ornamental Roofing, of which the following is a specification.

This invention relates to the art of roofing and refers more particularly to the production of ornamental flexible sheet roofing material of the character comprising a water-proofed base, coated with a granular or 10 comminuted mineral substance to protect the 15 water-proofing medium from the weather, and having an ornamental design applied thereto.

One of the objects of the invention is to devise an improved apparatus for creating 20 a design on the roofing after the layer of grit has been affixed by applying an additional layer of coloring material in the form of the design on top of the coating of grit.

Another object is to provide an apparatus 25 such as just set forth by which the design may be rapidly and effectively applied during the continuous traveling movement of the sheet about its guiding and feeding rolls.

In the accompanying drawings, Figure 1 30 is a diagrammatic view illustrating an apparatus embodying my invention. Fig. 2 illustrates a fragment of the stencil, and Fig. 3 represents a fragment of roofing made in accordance with my invention.

35 In manufacturing roofing of this character a suitable base is selected, which base may consist of a strip or sheet of flexible absorbent material, such as paper, cloth, felt or other fibrous material. This strip is 40 coated on one or both faces, or wholly or partially saturated, with a water-proofing medium, which may be of a bituminous, asphaltic or resinous composition, and which may be maintained in a fluid state by application of heat thereto. After the surface of 45 the sheet has been coated or impregnated with the water-proofing medium a layer of comminuted flaky or granular mineral substance, or grit, such as silica, shale, crushed 50 stone or slate, gravel or the like, is applied to the face thereof while the water-proofing material is in a fluid or viscous condition, so that the grit will adhere to the base.

The roofing is now ready to receive a suitable ornamentation which may be of any 55

preferred design or configuration. For example, a design may be such as to give the ocular impression of fancy tiling or shingles.

The sheet is in the form of a long strip 60 or ribbon and may be given a continuous traveling movement by means of suitable feeding and guiding rolls. After the layer of grit has been deposited the sheet is guided into association with a stencil which is preferably in the form of an endless ribbon 65 mounted on suitable rolls and driven at the same speed as the roofing sheet. The stencil and the roofing sheet move along together and at a certain point they come into association with a spray head from which a spray of coloring material or paint, preferably of a bituminous nature, is continually discharged. The supply of paint may be maintained in a suitable tank located in a 70 plane above and connected to the spray nozzle, the paint being maintained in a fluid condition by application of heat to the tank.

The spray issuing from the spray head 75 will pass through the open spaces in the stencil and will saturate the layer of grit on the roofing and become intimately associated with the substratum of waterproofing or binding medium. A stronger bond between the layer of grit and the base will 80 thereby be effected.

Referring to the drawings: The apparatus illustrated in Fig. 1 comprises a series of rolls between and about which the strip or sheet of felt or other base material 5 passes and by which the sheet is given a continuous traveling movement. 6 indicates the initial rolls, from which the sheet 5 passes down around rolls 7 located in a tank 8 which contains an asphaltic or other binding medium 9. Heat may be applied to the tank in any desired way to maintain the binder in a molten condition. After being immersed in the binding medium the sheet 90 may be passed upwardly, and, if desired, may be lapped back and forth around a suitable number of rolls 10 allowing the binder to cool. The sheet then passes beneath a hopper 11 containing the granular mineral substance. The hopper 11 is as long 95 as the sheet is wide so that a layer of grit will be deposited upon the entire sheet. The thickness of the layer of grit on the sheet may be controlled by placing the lower end of the hopper, or an independent 100

105

110

scraper, close to the upper surface of the sheet. Rolls 12 may be provided to roll the layer of grit into close association with the binder. The grit-coated sheet now 5 passes into operative relation to the design applying means. This comprises a stencil 13 which is preferably in the form of an endless ribbon of the same width as the sheet 5 and which is supported upon a suitable 10 number of rollers 14, the latter being driven at the proper speed so that the stencil and the sheet 5 move at the same rate. In the present instance a roller 15 is provided above the stencil and the sheet 5 is thereby 15 caused to travel with the stencil along the lower, vertical and upper sides of the rectangular figure in which the stencil is held by its mounting rolls.

A spray head 16 which is preferably positioned 20 beneath the upper run of the stencil is arranged to eject upwardly a spray of paint across the full width of the stencil and the sheet 5. The spray head may be supplied by a tank 17 located in a plane 25 above said head and connected thereto by a valved pipe 18, the tank containing a quantity of bituminous paint which may be maintained in a fluid state by applying heat thereto in any well-known way.

30 The stencil may be kept clean by a pair of rotary brushes 19 contacting opposite sides thereof. Any matter loosened by said brushes will fall into receptacles 20 therebeneath.

35 The paint ejected from the spray head 16 will pass through the interstices in the stencil and will saturate the coating of grit on the roofing and unite with the bituminous 40 binder of the base. In this manner a permanent and durable design may be rapidly applied to the roofing during the continu-

ous travel thereof about its feeding and guiding rolls.

The foregoing detailed description is not intended as a limitation of my invention to 45 the present disclosure.

The scope of the invention is pointed out in the appended claims.

I claim as my invention:

1. An apparatus for producing ornamental sheet roofing comprising means for causing a flexible base to travel between two points, means for applying a binder to said base, means for depositing a material upon the base to form a background, a stencil 55 positioned in close proximity to the background-carrying surface of the base, means for causing the stencil to travel with the base, and a paint spraying nozzle positioned to discharge coloring matter upwardly 60 through said stencil, the binder applying means, the background applying means, the stencil and the nozzle all being located between the two points of travel of the base.

2. An apparatus for producing ornamental sheet roofing comprising means for causing a flexible base to travel between two points, means for applying a binder to said base, means positioned to subsequently deposit a background upon said base, a paint 70 container provided with an upwardly projecting discharge nozzle, an endless ribbon stencil positioned in close proximity to the background-carrying surface of said base, and means for causing said stencil to travel 75 around said nozzle and with said base.

In testimony whereof, I hereunto set my hand in the presence of two witnesses.

WILLIAM P. DUN LANY.

In the presence of—

STEPHEN G. WOOD,

ALICE M. K. O'BRIEN.
